UNITED STATES PATENT OFFICE.

JOHN P. TALLON, OF PERRY POINT, MARYLAND.

GARDEN SPACER.

Application filed July 13, 1925. Serial No. 43,179.

To all whom it may concern:

Be it known that I, JOHN P. TALLON, a citizen of the United States, residing at Perry Point, in the county of Cecil and State of Maryland, have invented certain new and useful Improvements in Garden Spacers, of which the following is a specification.

This invention relates to garden spacers and is useful to landscape gardeners and others desiring ornamental effects, as well as to the person having a small garden.

In laying out small gardens where a large number of plants have to be placed, it is common to lay a series of parallel strings in one direction and another series of parallel strings crossing the others at an angle. Plants are then planted at the intersections of the strings. The designs are varied by varying the combinations of angles and the number of the strings. This system is very slow and necessitates a great deal of bending over and the making of many careful measurements.

In order to provide a means for making these careful measurements unnecessary and to save time, labor and expense in laying out a garden, by means of a simple hand device, has been a primary object of my invention.

Other objects of my invention are to provide such a cheap hand implement which will have means for adjusting the interval at which the plants are to be spaced, the marking portions being readily adjustable relative to each other and to the handle so that the manipulation of the implement may be facilitated, and so constructed that the opening made in the ground will readily close when pressure is made on the earth adjacent the opening.

Referring to the drawing wherein I have illustrated a preferred embodiment of my invention,

Fig. 1 is a front view slightly in perspective.

Fig. 2 is a sectional view on the line 2—2 of Fig. 1.

Fig. 3 is a side view.

Fig. 4 is a sectional view on the line 4—4 of Fig. 1.

In the drawings, the same reference characters refer to the same parts throughout the several views.

In order to properly manipulate my spacer, I have found that a straight handle

10 should be mounted midway of the length of the foot board or impression block support 11. The impression block support 11 is provided with elongated slots 12 arranged lengthwise with the support and in a plane with the axis of the handle 10. The handle 10 is secured midway of the ends of the support, between the slots and in an opening in the support as shown in Fig. 2. A suitable fastening means as the bolt 13 is provided to hold the handle 10 and support 11 in position relative to each other.

Beneath the impression block support 11, are two impression blocks 14. These blocks are preferably cylindrical and have grooves 15 along their sides for a purpose to be described. The bottom portion of each block is tapered as shown in all of the figures. The lower ends of the blocks 14 are flat to contact with a conical metallic point 17, the outer surface of which completes and forms a continuation of the conical surface 16 already referred to.

The metallic point 17 is provided with a stem 18 which extends through an opening extending axially in the impression block 14 and is long enough to extend through the slot 12. The upper end of the stem 18 is threaded and is provided with a wing nut 19. Between the wing nut and the block is placed a washer 20.

On the support 11 adjacent the side of each slot I have provided a scale 21 preferably marked in one-half inch intervals on each side, these half inch intervals being designated by one inch designations in such a way that when each block 14 is moved one-half inch away from the handle, the designations will show that the points of the blocks 15 have been moved an inch away from each other.

The adjustment of the blocks 14 and their points 17 is brought about by loosening the wing nuts 19 and sliding the blocks along to their proper adjustments and then tightening them to secure the blocks in place.

In using my spacer to make, for instance, the usual row formation lengthwise and crosswise of the garden, I use a string or cord along one side of the garden as a base line, the ground having first been prepared. One of the blocks is placed at the corner and the other along the line of the cord. The support is now pressed with the foot while the handle is held firmly in an upright position. Two holes will be made in the

earth. The handle is now moved with a slightly circular movement to loosen the earth from the blocks. The spacer may now be removed and moved so that one block 5 will re-enter one hole in the ground, the other block being pressed into the ground to make a third hole. This is continued across the end of the garden. The same is done at the side. After the completion of 10 these two rows, one of the springs or cords may now be shifted to the opposite side and the operation repeated. Having two opposite sides completed, it is only necessary to shift the string or cord one space at a 15 time and go the length of the row with the spacer. The rows will then be found to extend lengthwise and crosswise. In this way, the placing of a complete set of strings or cords across the garden, is obviated, thus 20 saving much time.

In making circular rows, circles of the desired diameter may be marked with a string or cord and nail and then placing the holes with spacer in the usual way.

25 In using the spacer, the handle may be used to lift both blocks from the ground and replace them at a new position or one may be kept partly in the ground and the other block swung to a position where the 30 new hole is to be made.

The grooves 15 leave ribs in the walls of the openings in the dirt. These ribs, when the plant is inserted in the hole, help break up the wall of the hole as the dirt is 35 pressed around the newly inserted plant.

Various other methods of use will be apparent to those skilled in the art.

While I have described and illustrated, in detail, an embodiment of my invention, I desire to have it understood that I do 40 not limit myself to the exact showing and that modifications and changes may be made without departing from the spirit of my invention and within the scope of the appended claims. 45

Having described my invention, what I claim and desire to secure by Letters Patent is:—

1. A garden spacer comprising two impression blocks, a support, means for adjustably securing the blocks to the support, a single handle extending from the support at a point between the blocks, the axis of the handle being parallel to the axes of the blocks. 50

2. A garden spacer comprising two impression blocks, a support to which the blocks are adjustably secured, the blocks having slots, means extending through the slots and securing the blocks to the support 60 in any one of several adjusted positions, a single handle extending from the support at a point between the blocks.

3. A garden spacer comprising two impression blocks, a support to which the blocks are adjustably secured, the blocks having slots, metallic points at the lower ends of the blocks, stems extending from the points, through the blocks and slots and means at the upper ends to secure the blocks and points in rigid relation to the support. 65

In testimony whereof I affix my signature.

JOHN P. TALLON.
